TOOL FOR REPLACING AUTOMOBILE HUB CAPS

Carl F. Caramelli, 905 Superba Ave., Venice, Calif.

Filed Nov. 6, 1962, Ser. No. 72,401

Term of patent 14 years

(Cl. D54—13)

FIG. 1 is a side elevational view of a tool for replacing automobile hub caps showing my new design;

FIG. 2 is an elevational view thereof as seen from the left of FIG. 1;

FIG. 3 is an elevational view thereof as seen from the right of FIG. 1; and

FIG. 4 is an isometric view thereof.

I claim:

The ornamental design for a tool for replacing automobile hub caps, substantially as shown.
